UNITED STATES PATENT OFFICE.

LUTHER R. ZOLLINGER, OF PHILADELPHIA, PENNSYLVANIA.

ANTICREEPING TIE-PLATE AND RAIL-JOINT SUPPORT.

No. 921,576.

Specification of Letters Patent.

Patented May 11, 1909.

Application filed December 19, 1908. Serial No. 468,339.

To all whom it may concern:

Be it known that I, LUTHER R. ZOLLINGER, a citizen of the United States, residing in the city and county of Philadelphia, State of Pennsylvania, have invented a new and useful Anticreeping Tie-Plate and Rail-Joint Support, of which the following is a specification.

In the devices heretofore employed for preventing the creeping of the rails, the anti-creeping device has been anchored to a single tie, thereby necessitating the employment of a large number of these devices, each working individually.

15 The object of my present invention is to devise a novel construction of an anti-creeping tie plate and rail joint support, wherein the rail is suitably anchored to a plurality of ties, preferably three or more, whereby the 20 tendency of the rail to creep in the direction of the traffic is resisted by the ballasted road bed between a plurality of ties through the tie plates and spikes and in turn through the bolts and splice bars and owing to the manner in which my novel construction of tie 25 plate is adapted to extend over a number of ties, the resistance to the tendency of the rails to creep is distributed over a large number or a plurality of cross ties, so that the 30 cross ties will be the more securely held in their ballasted bed, thereby preventing the shifting and bunching of the rails at the joint and maintaining the ties regularly spaced under all conditions which arise under traffic.

35 It further consists of a novel construction of an anti-creeping device which is adapted to support the rail joint and splice bars at their weakest point and resist the shearing tendency and vertical motion at the rail ends 40 by bridging between the ties, said tie plates being provided with means for holding the rail to gage so that the lapping of the rail ends is prevented and substantially the same line is maintained at the joint as is maintained through the body of the rail.

45 It further consists of a novel and simplified construction of an anti-creeping device comprising an integral piece of material adapted to protect the ties supporting the joint and 50 prevent the rail from creeping, the device being so constructed that the extra fastening and locking devices usually employed in devices of this character are entirely dispensed with, the only fastening means engaging the 55 anti-creep being that which is ordinarily

used to fasten the rail to the cross ties, namely a driven or screw spike.

It further consists of a novel construction of anti-creeping device, comprising a plate having a longitudinally extending, depending flange adapted to be embedded in each tie, said plate having on its rail supporting surface a rib against which the base flange of the rail abuts, said tie plate being adapted to receive suitable spikes or fastening devices 60 which pass therethrough into engagement with the different cross ties and also through the splice bars, whereby the tie plate and the rail is suitably anchored to a plurality of cross ties so that the resistance of the ballasted bed between a number of ties is employed to prevent the creeping of the rail, whereby the labor necessary to respace the cross tie, tamp the ties and firmly place them on a new foundation is entirely obviated.

70 It further consists of other novel features of construction, all as will be hereinafter fully set forth.

75 For the purpose of illustrating my invention I have shown in the accompanying drawing a preferred embodiment thereof which I have found in practice to give satisfactory and reliable results, although it is to be understood that the several instrumentalities of which my invention consists can be 80 variously arranged and organized and that my invention is not limited to the precise arrangement and organization of these instrumentalities as herein set forth.

85 Figure 1 represents a sectional view of an anti-creeping tie plate and rail joint support embodying my invention, the same being shown in assembled position with respect to the rail and the section being taken on line x-x, Fig. 2. Fig. 2 represents a side elevation of my device in assembled position and showing in addition a portion of the ballasted bed between the cross ties. Fig. 3 represents a side elevation of my novel construction of tie plate. Fig. 4 represents a plan view of my novel construction of tie plate showing the manner in which the same is located on a plurality of cross ties.

90 Similar numerals of reference indicate corresponding parts in the figures.

95 Referring to the drawings:—1 designates a tie plate embodying my invention, the length of this plate being such that it extends over two or more or preferably four cross ties. 2. The tie plate 1 on its under surface is 100

105

110

115

provided with a longitudinally extending depending rib or flange 3 which, as indicated most clearly in Fig. 1, is adapted to be seated on the different cross ties 2 and thereby prevent any lateral movement of the tie plate with respect thereto.

4 designates a rail flange engaging abutment, on the rail supporting surface 2 of the tie plate, said flange preferably extending longitudinally of the tie plate from one end to the other end thereof. The outer face of the flange 4 is preferably beveled as is indicated at 6.

7 designates apertures passing through the flange 4, said apertures being located at suitable distances apart in order that when the tie plate is placed in proper position over the cross ties, each aperture 7 will be located above a cross tie.

20 8 designates apertures through the tie plate on one side of the flange 4, in order that the ends of the tie plate may be securely anchored to the cross ties thereunder before a rail has been spiked into place.

25 9 designates apertures through the tie plate near each end thereof and located on the other side of the flange 4, said apertures being adapted to receive suitable spikes, so that when the fastening devices have been placed in the apertures 8 and 9, the tie plate will be securely anchored to the cross ties located at each end of said tie plate.

10 designates apertures adapted to receive the spikes and which are located at such distances apart that each of said holes will be above one of the cross ties when the tie plate is in position. It will be seen that the apertures 8 and 9 at each end of the tie plate are in staggered relation with each other or located in different transverse planes and the apertures 7 and 10 through which spikes pass to secure the rails and tie plate in position, are also located in different planes. It will thus be seen that the apertures for the fastening devices in the tie plate are located in such a manner as to give the best results without weakening the strength of such tie plate.

11 and 12 designate adjoining rails, the abutting or juxtaposed ends of which are suitably secured together by means of the splice bars 13 through which latter and the web of the rail passes suitable fastening devices, such as bolts 14 provided with suitable nuts 15. The splice bars 13 are preferably so constructed that they contact with the base flanges of the rail and the under side of the rail heads.

17 designates the spikes, it being noted that certain of these spikes pass through the splice bars 13 and through the apertures 7 and 10 in the tie plate 1. It will be noted that in the present instance the rib 3 on the under side of the tie plate 5 is shown as being preferably in the same place and extending

in the same direction as the rail engaging flange 4 on the rail supporting surface of this tie plate, but it is to be understood that the location of this flange 3 may be varied without departing from the spirit or scope of my invention.

My novel construction of tie plate and rail support can be used with great economy over the different constructions of tie plates, heretofore employed in this art, wherein each individual tie plate was anchored to but a single tie, since my device is anchored to any desired number of ties, as preferably four, and receives the resistance of the ballast 16 between said ties and each cross tie and the fastening devices on said cross tie co-act with each other to perform their function and maintain the rail in a better line through the joint and the surface of the wooden ties is protected over their entire face from the abrasions of the rail, as will be evident to those skilled in this art.

It will be apparent that in order for the rail to creep in cases where my present device is employed, it will be necessary not only for the tie plate and the plurality of ties to which such tie plate is secured to shift from their normal position, but the ballast bed between a plurality of cross ties must also shift from its normal position before any movement of the rail will be permitted; wherefrom it will be apparent that by my novel invention, the liability of the rail to creep will be in every case reduced to a minimum, and in the great majority of cases under normal or ordinary traffic conditions, entirely obviated, and so far as I am aware I am the first to produce a concrete, unitary structure possessing the features of novelty and advantage hereinbefore set forth.

It will be apparent that while I have shown my present invention as adapted to engage and co-operate with four ties, since I have found in practice that this construction gives excellent results, by reason of the fact that the device is nicely and mechanically balanced by the ends of the tie plate being secured to the two outer ties as indicated, while the two inner ties serve in conjunction with the central portion of the tie plate, splice bars and their adjuncts, to properly sustain the splice bars and their adjuncts. It will be evident that if desired, I may prolong the tie plate sufficiently to engage six or more ties instead of four or less without departing from the spirit of my invention.

It will be further apparent to those practically skilled in the art that my invention does not reside merely in lengthening the tie plates now in use, but consists in collocating and adapting a tie plate of sufficient length to extend over a plurality of ties so as to protect the surfaces of said plurality of the ties and to efficiently and practically support the splice bars and the abutting ends of the rails,

so that in conjunction with the ballast a lasting and efficient anti-creeping tie plate and rail joint support is attained, which so far as I am aware, has no counterpart in the prior art, and while it is apparent to those skilled in the art that slight changes may be made in the manner of assembling and fastening the tie plate splice bars and rails to the cross-ties, I reserve to myself the right to make all such changes as will come within the scope of my invention.

Having thus described my invention, what I claim as new and desire to secure by Letters Patent, is:—

1. The combination of four ties, ballast therebetween, a tie plate supported upon said ties, and having the oppositely located openings 8 and 9 for securing the ends of said plate to the outer ties, a rail flange engaging abutment 4, said tie plate having four openings 7 therein, extending through said abutment, and the four oppositely located openings 10, a tie engaging flange 3 in the same vertical plane as the abutment 4, the meeting ends of a pair of rails supported upon said plate, splice bars for said rails, fastening devices for said rails and splice bars, certain of said fastening devices passing through the openings 7 and both of said flanges and fastening devices common to said splice bars, tie plate and two intermediate ties.

2. In a device of the character described, the combination of four ties, a tie plate supported on the upper surfaces of said ties and having an upper and lower longitudinally extending flange in the same vertical plane, a pair of rails, means for securing the meeting ends of said rails, upon said tie plate, said means including fastening devices passing through both of said flanges and means for securing the outer and intermediate portions of said tie plate to the two outer and the two intermediate ties respectively.

3. As an improved article of manufacture, an anticreeping tie plate and rail joint support of sufficient length to engage a plurality of ties, a longitudinally extending flange 4 on the top of said tie plate and a longitudinally depending tie engaging flange projecting from the bottom of said tie plate, said flanges 50 being in the same vertical plane, a plurality of oppositely arranged openings 8 and 9 at the opposite ends of said tie plate for enabling the latter to be secured to the outer ties, a plurality of openings 7 extending through 55 said flange 4 for enabling the rail bases to be secured in position, said openings 7 passing through both of said flanges and a plurality of oppositely located openings 10 arranged intermediately of said openings 9. 60

4. As an improved article of manufacture, an anticreeping tie plate and rail joint support consisting of a base or body portion of sufficient length to engage a plurality of ties, a longitudinally extending flange on the top 65 of said tie plate, forming an abutment for the bases of the rails supported thereby, and a depending longitudinally extending flange projecting from the bottom of said tie plate and adapted to engage said plurality of ties, 70 said tie plate having at its outer extremities, a plurality of openings 7, 8, 9 and 10, through which fastening devices are adapted to pass to engage the outer ties upon which said tie plate is adapted to be supported and said tie 75 plate also having the pairs of intermediate openings 7 and 10 adapted to receive fastening devices which are adapted to engage the inner or intermediate cross ties supporting the intermediate portion of said tie plate, and 80 said openings 7 passing through both of said longitudinally extending flanges.
